UNITED STATES PATENT OFFICE.

HORACE B. CAMP, OF AKRON, OHIO.

DESIGN FOR A BUILDING-BLOCK.

SPECIFICATION forming part of Design No. 30,550, dated April 11, 1899.

Application filed March 13, 1899. Serial No. 708,970. Term of patent 14 years.

To all whom it may concern:

Be it known that I, HORACE B. CAMP, a citizen of the United States, residing at Akron, Summit county, State of Ohio, have invented and produced a new and original Design for Building-Blocks, of which the following is a specification; reference being had to the drawings forming a part thereof.

In said drawings, Figure I represents a view in perspective of my building-block; Fig. II a top plan view, Fig. III a side elevation, and Fig. IV an end elevation, of the same.

The leading feature of the design consists in the shape and configuration of the top of the building-block. As shown in the drawings, the block A is rectangular in section and is provided with a groove or recess B, arranged transversely of its top. The sides of

said recess b are straight throughout their entire length and the bottom b' is flat and substantially parallel with the top of the block. A web C extends between the central portion of the bottom of said recess and the base of the block and is formed integral with said base and bottom portion. 25

I claim—

The design for a building-block, substantially as shown and described.

In witness whereof I sign this application, in the presence of two witnesses, this 10th day 30 of March, 1899.

HORACE B. CAMP.

Witnesses:

C. I. HENDERSON,
G. H. FOSTER.
